MAX VON RECKLINGHAUSEN, OF PARIS, FRANCE, ASSIGNEE, BY MESNE ASSIGNMENTS, TO COOPER HEWITT ELECTRIC COMPANY, OF HOBOKEN, NEW JERSEY, A CORPORATION OF NEW JERSEY.

ELECTRODE FOR GAS OR VAPOR ELECTRIC APPARATUS.

1,110,574.

Specification of Letters Patent. Patented Sept. 15, 1914.

Original application filed February 14, 1903, Serial No. 143,317. Divided and application filed February 5, 1907, Serial No. 355,845. Divided and this application filed April 23, 1911. Serial No. 624,105.

To all whom it may concern:

Be it known that I, MAX VON RECKLINGHAUSEN, a subject of the Emperor of Germany, and resident of Paris, France, have invented certain new and useful Improvements in Electrodes for Gas or Vapor Electric Apparatus, of which the following is a specification.

The present invention is applicable to the general class of gas or vapor electric apparatus invented by Peter Cooper Hewitt and described and shown in certain patents issued to him on the 17th day of September, 1901.

15 In apparatus of this class whether used for the purpose of giving light or for any other purpose, it has been customary, when found convenient, to use as the material for one or more of the electrodes a conducting fluid such as mercury. During the operation of the apparatus some of this mercury is vaporized and afterward cooled, usually in a special cooling chamber. Hitherto no special means have been devised for securing an accurate re-distribution of the mercury after the condensation due to cooling, although devices have been suggested for carrying some of the mercury which is carried away from the negative electrode back to the said electrode after condensation, say, through a special tube provided for the purpose.

The present invention aims at providing a more accurately gaged re-distribution of the mercury, as will fully appear herein-after.

For example, I may provide suitable pockets for containing the several electrodes of mercury or other conducting fluid, such pockets being devised so as to contain the proper amount of fluid to serve as an electrode and to present within the chamber of the apparatus a suitable amount of surface for the purpose for which the apparatus is designed.

I may then so dispose the cooling chamber in which the greater part of the condensation takes place with relation to the several pockets as to provide for a return of the mercury which may have been withdrawn from the said pockets during the operation of the lamp, or by any means whatsoever to the said pockets in succession, so that any

55 pocket which shall have received its proper amount of mercury, or other conducting fluid will, on the entrance of any more fluid, of condensation overflow and transfer the overflow to the next pocket and so on until all the pockets in the series are suitably filled. I may accomplish this by giving to 60 the apparatus a suitable slope running from the cooling or condensing chamber downward whereby the force of gravity will carry the condensed vapors from pocket to pocket as described.

65 Should it be desired to utilize a non-fluid or solid substance as one of the electrodes, or a fluid of another character, or should it for any reason be undesirable to deliver the condensed vapor to one of the electrodes, the 70 tube may be turned away from the general downward slope and may thus be removed from the path of flow.

It is now known that apparatus of this class is often provided with a considerable 75 number of electrodes. For example, a well-known form of apparatus contains a single negative electrode and a plurality of positive electrodes, while a supplemental electrode is often employed as one terminal of a 80 direct current circuit adapted to maintain the passage of current of one direction through the apparatus.

I have illustrated my invention in the accompanying drawings, in which Figure 1 is 85 a section of a gas or vapor electric apparatus embodying my invention; Figs. 2 and 3 are similar views of modifications.

Referring to the drawings, 1 is a container 90 adapted to inclose a conducting gas or vapor and being provided with pockets 2, 3, 4, 5 and 6, as shown. These pockets are adapted to contain a conducting fluid which in this instance is represented as mercury, and the pockets 2, 3 and 5, may be assumed to contain the mercury constituting positive electrodes, while the pocket 4, may contain the mercury constituting the negative electrode, and the pocket 6 may contain the mercury 95 constituting the supplemental electrode. 100 Suitable lead wires are connected through the walls of the pockets with the electrodes contained therein.

It is unnecessary to give in detail the 105 operation of an apparatus of this sort further than to say that such operation has for

one of its effects the vaporization of a portion of the conducting fluid and the circulation of the vapor through the apparatus.

As a feature of the apparatus, a cooling chamber, as 7, is generally provided, and in this instance I locate such chamber at the summit of the apparatus, and incline the tubular portion 1 with respect to the said cooling chamber so as to give to the mercury 10 which is condensed therein a tendency to descend along the tube by the action of gravity. In its descent the condensed vapor will first enter the pocket 2, and in case that pocket has been depleted of a portion of its mercury, the descending mercury will now refill it, and when such refilling has taken place, the pocket will overflow and the mercury will pass into the next pocket in the series and so on. In this way the several 20 pockets are maintained full, or nearly so, at all times, and the mercury which is withdrawn by the operation of the apparatus is re-distributed in such a way as to restore normal conditions.

25 In Fig. 2 the same principle is illustrated, the pockets in this instance being two in number, one of them, as 8, containing the positive electrode, and the other, as 9, the negative electrode. In both instances, suitable lead-wires are connected through the walls of the pocket with the electrodes contained therein.

Fig. 3 illustrates a construction in which one of the electrodes, say the supplemental 35 electrode, appearing at 10, is of some solid substance such as iron. The electrode 10 is arranged in a raised portion of the tube and is not subject to being fed by the downward flow of the conducting fluid, as is the case 40 with the other electrodes.

Short circuits between the electrodes during the transfer of fluid from one pocket to another may be prevented by introducing obstructions just in advance of each pocket, 45 as illustrated as 11, 11. The fluid on striking these obstructions will be momentarily checked and on leaving them will be accelerated so that there is not likely to be a continuous stream of mercury between two successive pockets.

Experiment has proved, however, that if a narrow channel for the descent of the mercury from electrode to electrode be formed in the glass, the short-circuit which may 55 then be established between successive electrodes will affect the stream of mercury

which is so narrow that it will be dissipated or vaporized by the short-circuit without serious interference with the action of the apparatus. This construction may be substituted for the one above described.

The means already described are merely illustrative of typical forms of devices whereby the present invention may be carried out. Many other embodiments of the invention might be made without substantial departure from the principle of this invention.

This application is a division of my application Serial Number 355,845, filed February 5, 1907, which in turn is a division of my application Serial Number 143,817, filed February 14, 1903.

I claim as my invention:

1. A mercury vapor apparatus comprising 75 an exhausted container, said container having a tubular portion making an oblique angle to the horizontal and a condensing chamber located at the upper end of the inclined portion, a mercury electrode at the lower end 80 of said container and at least one electrode located on the under side of said tubular portion intermediate between said condensing chamber and said first named electrode.

2. A vapor electric apparatus comprising 85 an exhausted container, said container including an inclined portion making an oblique angle with a vertical, a condensing chamber at the upper end thereof draining into said inclined portion, a plurality of electrodes 90 therefor, one being a mercury electrode at the other end of said inclined portion located to receive the condensation passing through said inclined portion, the remaining mercury electrodes being located above said first 95 named electrode in the said inclined position.

3. A mercury vapor apparatus comprising 100 an exhausted container, said container including two tubular portions making an oblique angle with a horizontal, a plurality 105 of electrodes therein, one being a mercury electrode located in a pocket below the other electrodes and communicating with both said tubular portions, the other electrodes being located in said extensions and at least one of 110 said electrodes so located being a solid anode.

Signed at Paris, France.

MAX VON RECKLINGHAUSEN.
